BRANSON BREEDEN, OF LEXINGTON, VIRGINIA.

Letters Patent No. 90,490, dated May 25, 1869.

IMPROVED WASHING-MACHINE.

The Schedule referred to in these Letters Patent and making part of the same.

To all whom it may concern:

Be it known that I, BRANSON BREEDEN, of Lexington, in the county of Rockbridge, and State of Virginia, have invented a new and improved Washing-Machine; and I do hereby declare that the following is a full, clear, and exact description of the construction and operation of the same, reference being had to the accompanying drawings, making a part of this specification, in which—

Figure 1 is a vertical section through line x x of fig. 2.

Figure 2 is a front view, a portion of it being broken out.

In this invention a set of vertical beaters is employed, operated by a rotary shaft, and combined with a revolving tub, an apparatus for raising all the beaters at once, and a heater for keeping the water at any desired temperature during the operation.

In the drawings—

H represents the heater or furnace.

A, a circular metallic tub, resting upon the upper surface of the heater, and having a cog-rim, a, around it, gearing with a cog-wheel, B, enables the operator to rotate the tub about its vertical axis, by means of a crank and shaft, C C'.

D D' D'', &c., are a set of beaters, attached to vertical sliding rods d d' d'', weighted, as seen at W W' W'', &c.

Each of the rods has a projecting arm, e, on its rear side.

The crank-shaft C supports a horizontal drum or roller, C'', provided with a set of pegs, c c, which, coming in contact with the arms e e, raise the beaters and drop them one after another as the cylinder is rotated.

At the same time that the cylinder thus performs

this function, it rotates the tub A, and causes the beaters to operate upon all the clothes therein uniformly, thereby thoroughly cleansing them.

The beaters may be attached to a box, F, which can be fastened down to the frame of the apparatus by a hasp, h.

Above the box F the rods d d', &c., pass through a horizontal plate, G, which can be raised or lowered by a lever, L, so as to raise or depress all the rods and beaters at once, thereby throwing them into or out of connection with the operating-cylinder.

The whole device is simple, easy of operation, and exceedingly efficient, thoroughly cleansing the clothes, and removing stains, grease, &c., from them without tearing or injuring them, as is necessarily done where they are scrubbed over a corrugated board, either by hand or otherwise.

I do not claim any specific part of this machine as my invention, when considered independently of the other parts; but having thus described my invention,

What I do claim, and desire to secure by Letters Patent, is—

The washing-machine herein described, consisting essentially of the furnace H, rotary-tub A, cog-rim a, gear B, crank and shaft C C', pegged or toothed cylinder C, beaters D, provided at their upper ends with weights W W' W'', the plate G, and lever L, all constructed and arranged in the manner and for the purpose specified.

The above specification of my invention signed by me, this 22d day of February, 1869.

BRANSON BREEDEN.
